UNITED STATES PATENT OFFICE.

HARRY C. COCHRANE, OF BROOKLYN, NEW YORK.

METAL BARREL.

1,325,231.

Specification of Letters Patent. Patented Dec. 16, 1919.

Application filed March 28, 1919. Serial No. 285,714.

To all whom it may concern:

Be it known that I, HARRY C. COCHRANE, a citizen of the United States, and resident of Brooklyn, in the county of Kings and 5 State of New York, have invented certain new and useful Improvements in Metal Barrels, of which the following is a full, clear, and exact specification.

This invention relates to metallic receptacles of the barrel type, and has for its object to provide a receptacle of this kind in which will be combined great durability and simplicity of construction. One important 10 object is to insure against leakage resulting from transportation of the barrels during 15 which they are necessarily brought into contact with one another and are roughly handled generally.

Another object is to prevent the 20 placement of any part of the interlocking connections between the body of the barrel and its head during such treatment. Further objects will appear as the description 25 proceeds.

The invention will be first hereinafter 30 described in connection with the accompanying drawings, which constitute part of this specification, and then more specifically defined in the claims at the end of the description.

In the accompanying drawings, wherein similar reference characters are used to designate corresponding parts throughout the several views:—

Figure 1 is an elevation of a receptacle or barrel constructed substantially in accordance with this invention, the upper portion being shown in section, and

Fig. 2 is an enlarged sectional view 40 through one of the joints or connections between the body and head.

The walls A of the body of the receptacle or barrel are preferably made of a single piece of sheet metal bent to conform to the usual 45 barrel shape and having its upper and lower edge portions bent into the form of partially closed beads B, there being a circumferential depression or groove C in the outer surface of the walls A where each of the beads B merge into the body portion proper. The bead B is formed by first bending the metal outward from said groove C and then bending said metal inward and downward, so 50 that the open portion of the bead faces toward the interior of the barrel.

Each head D of the receptacle may be

made in the same manner of a sheet metal disk having its central portion depressed as at d and its peripheral edge curled to form a partially closed bead E, said bead being 60 formed by bending said edge portion upwardly, inwardly and downwardly to conform to the interior of the bead B. The opening in the bead E is presented to the horizontal flat portion of the head directly 65 adjacent said bead. A rod F may be used as a filler within the bead E in order to increase the solidity of the connection between the head and body.

To further strengthen and reinforce this 70 connection, a band or strip G, which may be of sheet metal the same thickness as that used for the body and head of the receptacle, is bent around the bead B with one edge arranged in the depression or groove C 75 and its other edge arranged substantially on the same level with the inner edges of the beads E and B, see Fig. 2. These inner edges of the beads E and B and of the band G are beveled, as at e, b and g, all of said 80 bevels facing inwardly toward the center of the joint or connection between the body and head. All of these edges are also spaced away from the outer surface of the head, so that a jagged space is left between said 85 outer surface of the head and the beveled inner edges of said beads and band into which space a filling of brass or other suitable material H is poured and allowed to 90 harden for sealing the joint.

This brazing material is also extended a short distance beyond the beveled edge g and is built up to a desired extent along said edge, as at h, in order to form a shoulder or abutment for the same which tends to prevent said edge from being jarred away from the bead B and the joint being opened in that way. It will be noted that owing to the jagged formation of the space filled by the brazing material, there is 100 a similar shoulder or abutment formed behind the beveled edges b and e, each of said edges being thus held separately against any tendency to spring out and open the joint. A filling of brazing or soldering material K 105 may also be placed in the groove C at the edge of the band G which terminates in said groove, thus securing that edge in proper position.

In constructing the barrel or receptacle, 110 the heads D may be first formed with the beads E inclosing the rods F, and the beads

B, which may have been previously partially formed, then closed or completely formed around the bead E, after which the band G is put in place and the brazing or 5 soldering material allowed to flow and harden in the spaces as hereinbefore described. It will be noted that this brazing or soldering material is in each instance arranged in a depression so that it is not exposed on the 10 outer surface of the receptacle where it could possibly be struck by another receptacle in transportation or storage. The interlocking of the edges of the beads and outer band with the brazing material makes 15 the joint between the body and heads of the receptacle strong enough to withstand considerable wear and tear, which it is bound to receive owing to the rough handling such receptacles get, without causing a leak or exposing the contents of the receptacle. 20

Having thus described my invention, what I claim as new and desire to secure by Letters Patent of the United States is:—

1. In a receptacle of the character described, the combination with a body portion having an open bead at its end, the opening of said bead facing inwardly, of a head having a bead formed around its peripheral edge and arranged on its outer face 25 to conform to and fit within the bead on the body portion, the edges of said beads being spaced slightly from the outer surface of the head, a filling of soldering material arranged in the space between said edges of 30 the beads and said outer surface of the head and in which said edges are embedded, said soldering material being thus arranged in the depression of the head formed by the outwardly projecting bead thereon, and a separate band bent into the form of a bead inclosing the bead on the body portion and having one edge embedded in said soldering material in the depression of the head, the other edge of said band being arranged in the external groove at the juncture of the body portion and its bead, and another filling of soldering material arranged in said external groove at the edge of the band therein. 35

2. In a receptacle of the character described, the combination with a body portion having an open bead at its end and an external groove at the juncture of said bead 40

with the body portion, the opening of the bead facing inwardly, of a head having a bead formed around its peripheral edge and arranged on its outer face to conform to and fit within the bead on the body portion, the edges of said beads being spaced slightly from the outer surface of the head, a filling of soldering material arranged in the space 45 between said edges of the beads and said outer surface of the head and in which said edges are embedded, said soldering material being thus arranged in the depression of the head formed by the outwardly projecting bead thereon, a separate band bent into the form of a bead inclosing the bead on the body portion and having one edge embedded in said soldering material in the depression 50 of the head, the other edge of said band being arranged in the external groove at the juncture of the body portion and its bead, and another filling of soldering material arranged in said external groove at the edge of the band therein. 55

3. In a receptacle of the character described, the combination with a body portion having an open bead at its end, the opening of said bead facing inwardly, of a head having a bead formed around its peripheral edge and arranged on its outer face to conform to and fit within the bead on the body portion, the edges of said beads being spaced slightly from the outer surface of the head, and a filling of soldering material arranged in the space between said edges of the beads and said outer surface of the head and in which said edges are embedded, said soldering material being thus arranged in the depression of the head formed by the outwardly projecting bead thereon and the edges of said body and head beads, which are embedded in the soldering material, being beveled and facing inwardly toward the center of the joint for the purpose specified. 60 65 70 75 80 85 90

In testimony whereof I have signed my name to this specification.

HARRY C. COCHRANE.
